UNITED STATES PATENT OFFICE.

LEWIS W. HEATH, OF GRAND RAPIDS, MICHIGAN.

APPARATUS FOR PLAYING DUPLICATE WHIST.

SPECIFICATION forming part of Letters Patent No. 561,786, dated June 9, 1896.

Application filed December 11, 1895. Serial No. 571,771. (No model.)

To all whom it may concern:

Be it known that I, LEWIS W. HEATH, a citizen of the United States, residing at the city of Grand Rapids, in the county of Kent 5 and State of Michigan, have invented certain new and useful Apparatus for Playing Duplicate Whist, of which the following is a specification.

This invention relates to a new and useful 10 apparatus designed for playing the game of duplicate whist, and the same consists, in combination with raised strips, of a metallic spring secured thereto, with free ends adapted to hold the cards and retain them in place in the 15 card-holder.

It also refers to a card-holder for holding the cards to be used in playing duplicate whist, the same being composed of two wings or parts hinged together, so that when the 20 cards are in place it may be folded so as to have the appearance of an ordinary book, and can be opened so as to present a plain upper surface which sustains the cards in position.

25 It also consists in an apparatus or holder for cards in playing duplicate whist made in two parts and hinged together, having the required number placed on the back side, so as to be entirely concealed when the leaves 30 are opened and to be disclosed to view when the leaves are closed.

The objects of my invention are, first, to furnish a convenient method of securing the cards in position upon the holder by means 35 of metallic springs having sufficient resiliency to enable the user to place the cards in position and sufficient strength to retain them securely in place when put into the holder; second, in a holder constructed in two parts 40 hinged together so as to be folded or shut like an ordinary book, so that the holder when closed and placed in the case has the appearance of a simulated book and discloses its corresponding number on what appears to be 45 the back of the book; third, in having the requisite number of the set placed upon the back so as to be entirely concealed from view when the holder is open in readiness for use, and, fourth, in the details of construction 50 hereinafter described.

The outfit for playing duplicate whist by my method preferably consists of, first, decks

of ordinary playing-cards, as many decks as will make a game last a moderate length of time, provided the number is a multiple of 55 four; second, a series of holders, which are hereinafter described, as many in number as there are decks of playing-cards, and consequently numbered on the edges so as to be entirely concealed when opened; third, thirteen 60 counters such as are in familiar use at card-tables, and, fourth, a score-sheet.

The holders being numbered and all being constructed substantially alike, one of them 65 is a sample of all, and therefore the description of one will be sufficient.

In order to assist in the description, I have provided three figures of drawings, in which—

Figure 1 is a plan view of my newly-invented card-holder opened in place to receive 70 the cards on its upper side, one of the spaces being filled with cards. Fig. 2 is a perspective view of one of the holders closed into the form of a book, showing the back of the book with the number of the holder; and Fig. 3 is 75 a sectional view on line X X of Fig. 1.

Similar letters refer to similar parts throughout the several views.

A A represent the two wings or leaves of the card-holder, the same being hinged together by means of the hinges C C, said hinges C C being constructed in the ordinary manner and being attached to the longitudinal strips B B, which longitudinal strips are secured by glue or other suitable means to the 85 inner edges of the wings A A.

In the example of my invention shown in the drawings I have shown an ordinary butt-hinge; but any form of hinge may be used, the same being preferably placed so that when 90 the wings are folded together they will not appear on the back side or what simulates the back part of the book.

E E are transverse strips glued or otherwise suitably attached, one to each wing, as shown 95 in Fig. 1, and adapted to raise the springs D D a sufficient distance above the face of the wings A A to allow the cards to be slipped under the springs and thereby retained in position.

The springs D D are made of metal, preferably a flat piece, and secured at their centers to the cross-strips E, one to each strip. The free ends of the springs are preferably

turned up slightly in order to facilitate the insertion of the cards beneath the springs. These springs may be attached to the cross-piece E by means of a rivet, a screw, or any 5 well-known means.

In Fig. 1 I have shown a package of cards F placed beneath one end of the spring D in order to show the relative position of the cards to the spring when the holder is used 10 to retain the cards in position. The height of the strip E should be, preferably, about that of one-fourth of an ordinary pack of cards, so that when the cards are placed in position the spring D will be substantially parallel 15 with the face of the transverse strips E. At one end of one of the strips E, I place a letter "N" or a star or any other suitable means to designate what in duplicate whist is usually called "north." At the left of the point 20 marked "North" is placed, preferably upon the spring D, the word "Lead," in order to show in which direction the lead is to begin, the other holders to be each provided with a similar mark indicating where the lead begins. 25

In playing what is ordinarily known as the "original hands" the card-holders might well be placed upon the card-table so that the designator will point toward the north. Thus 30 placed the strip E of the frame, which, as above stated, is provided with a mark to designate north, and which I have called the "designating-arm," will in a series of any number of hands played be situated at the north. 35

In the holders numbered on the back side, as above described, 1, 5, 9, 13, and 17, the said designating-word "Lead" will lie to the east; but in the holders numbered 2, 6, 10, 14, and 18 the said designating-word "Lead" will lie 40 to the south. In the holders numbered 3, 7, 11, 15, and 19 the said designating-word "Lead" will lie to the west, and in the holders numbered 4, 8, 12, 16, and 20 the said designating-word "Lead" will lie to the north. 45

The game of duplicate whist is now so well understood that its method need not here be pointed out in greater detail.

When four persons are playing as partners at the table, a holder constructed in accordance with my invention is placed in the center so that the designating-strip points to the north. The dealer is the person facing the designating-arm, and the leader will be the person next to him at his left in whist order. 55 The cards of each player are played immediately in front of him. The cards of each trick are face downward when the trick is completed, and the partners score to themselves one for each trick taken. When the 60 hand is finished, the fifty-two cards of the deck lie in four packages before each player, facing downward. Each player places his own package on the holder at his right beneath the free end of the spring, and the holder is thus furnished with its four packages, returned to the case reversed or laid 65

aside. Like play proceeds as to the other packages and as to the other holders intended to be used, so that when the original play ends each of the twenty (more or less) holders is furnished with four packages of cards at rest in the four positions beneath the four free ends of the springs, each package being the separate thirteen cards which each player has played in his hand. All the holders may then be placed in the case in reverse order. At the end of each hand a score-card is used, and in the vertical column headed "Original play," in the line corresponding in number with the number found on the back of the holders when closed, is entered the number of tricks which each side took. The card which was the trump in each hand must of course be preserved. This may be done either by facing that card differently from its fellows or by writing the suit and size of the trump-card upon a separate card and slipping it in the hand where the trump-card lies, or by prior agreement that a certain suit shall be trump during the entire game. 75 80 85 90 95 100

In practice I desire to have a case simulating a small bookcase and adapted to receive the number of holders to be used—say twenty, in which case when these holders are folded and placed in it, it would simulate a small bookcase having twenty volumes of small books, and instead of piling the holders in a pile they may be folded and placed in the case, the back first, so that nothing but the edges or fronts of the simulated book can be seen, thereby concealing entirely the numbers on the back of the holders. 105 110 115 120 125

The duplicate play is thus managed, it being premised that the players maintain the same position at the table which they occupied in the original play: Any one of the card-supplied holders is taken from the case and placed upon the table with the designating-strip pointing not to the north, but to the east, or, if preferred, indifferently to the east 110 or the west. By this means the cards which the north and south players use in the original play are shifted one-quarter of a circle around the table and fall to their opponents, and the cards which the east and west players use in the original play are shifted one-quarter of a circle around the table and fall to their opponents. There is of course no dealer on the duplicate play; but the person corresponding to the dealer is the one sitting 120 to the left of the original dealer, and the leader is the player sitting next to him to the left. 130

During the duplicate play, as there is no longer any need of preserving the integrity 125 of the several players' packets, the holders may be laid aside after each player has removed from the holder in front of him the packet therein contained, or the cards may be returned to the holder. Such removal takes 130 place, of course, hand by hand as each hand is ended. The cards are then placed in the

middle of the table and bunched in tricks, as in ordinary whist, or returned to the holders. On the duplicate play the counters may be dispensed with and the tricks counted, or 5 counted with the counters originally used. The number of tricks made by each side is entered on the score-card in a vertical column which may be headed "Duplicate play."

Care should be taken in removing the cards 10 from the holders not to examine the number on the back side of the holder until the hand has been played through. In my device it is not easy to examine the number, for the reason that it is entirely concealed as long as the 15 holder is open. Any device should be avoided which might assist the player in remembering any card which has fallen or unusual play made in the original hands. When all the 20 holders have been played through, a footing of the score-card will indicate the winner, it now being evident that luck has been eliminated, for each team of two players has played the same cards which their adversaries had previously played.

25 Having thus described my invention, what I claim to have invented, and desire to secure by Letters Patent, is—

1. In a card-holder for playing duplicate whist, the combination with the holder proper, 30 of a transverse strip approximately the thickness of thirteen cards secured to the face of the holder, and a metallic spring attached intermediate its ends to said strip and adapted

with its free ends to clamp packages of cards to said holder, substantially as described. 35

2. In a card-holder for playing duplicate whist, the combination of two wings hinged together and adapted to be folded to simulate a book and provided on the back with a mark to designate its number so that when opened 40 the mark will be concealed, a transverse strip approximately the thickness of thirteen cards attached to the face of each wing, a metallic spring secured intermediate its ends to said strip and at right angles thereto and adapted 45 with its free ends to clamp packages of cards to said holder, substantially as described.

3. In a card-holder for playing duplicate whist, the combination of two wings A hinged together, the longitudinal strips B each approximately the thickness of thirteen cards attached to the adjacent edges of said wings, hinges C secured to said strips, transverse strips E attached centrally to the faces of said wings, a metallic spring secured intermediate its ends to each of said strips E and at right angles thereto, said springs being adapted with their free ends to clamp packages of cards to said holder, substantially as 55 described. 60

In witness whereof I have hereunto set my hand and seal in the presence of two witnesses.
